Corporation, a corporation of Illinois
Filed Jan. 2, 1962, Ser. No. 163,732
2 Claims. (Cl. 259—96)

This invention relates to fluid handling, and more particularly to a fluid handling apparatus.

A primary object of this invention is to provide a new and improved fluid handling apparatus.

Another object is to provide a new and improved apparatus for stirring a body of fluid and discharging a portion of the fluid from the body of fluid.

A further object is provision of a new and improved fluid handling apparatus including means for holding a body of fluid, and means operatively associated with the first means for pumping part of the body of fluid and discharging within the body of fluid a portion of the pumped fluid for effectively stirring the body of fluid and concurrently discharging from said body of fluid another portion of the pumped fluid.

A more specific object is provision of new improved fluid handling apparatus in the form of an immersion type centrifugal pump having a pumping chamber and a cooperating rotating impeller having generally radially extending blades in the chamber, the pump having an inlet adapted to be immersed in a body of fluid and an outlet communicating with the chamber for discharging a portion of the fluid from the body of fluid, a part of the pump having an outer side and on opposite inner sides defining a wall of the chamber generally parallel to and facing the blades with a series of passages in the part opening through these sides, the passages being inclined generally in the direction of rotation of the impeller adjacent the respective passage and toward the outer side of the part for directing high velocity jets of fluid in a pattern toward the bottom and sides of a container to produce rotary turbulence and effective stirring of the body of fluid.

Other objects and advantages will become readily apparent from the following detailed description taken in connection with the accompanying drawings, in which:

FIGURE 1 is an elevational view of a preferred embodiment of the invention, with parts broken away for clearer illustration;

FIGURE 2 is an enlarged horizontal section taken generally along the line 2—2 of FIGURE 1, or FIGURE 3 but to the same scale; and

FIGURE 3 is a fragmentary vertical section taken generally along the line 3—3 of FIGURE 2.

While an illustrative embodiment of the invention is shown in the drawing and will be described in detail herein, the invention is susceptible of embodiment in many different forms, and it should be understood that the present disclosure is to be considered an exemplification of the principles of the invention and is not intended to limit the invention to the embodiment illustrated. The scope of the invention will be pointed out in the appended claims.

The invention is, in brief, directed to an apparatus for stirring fluids such as liquids to mix the liquid with particles and discharging a portion of the mixed fluid. A body of fluid is pumped and divided into a first portion which is discharged from the body of fluid and another portion which is discharged within the body of fluid in a manner for effectively stirring the body of fluid. The apparatus has an inlet within a body of fluid and a pumping chamber in which part of the body of fluid is divided into a first portion which is discharged from the body of fluid and another portion which is discharged within the body of fluid so as to provide turbulence for effectively stirring the body of fluid.

2

Referring to the drawings, the fluid handling apparatus includes first means in the form of a container 10 for holding a body of fluid 11, and second means illustrated in the form of a pump 12 having inlet means provided as by a suction port 14 through which part of the body of fluid is drawn into a pumping chamber 15 so that it is confined and its pressure increased. This part of the fluid has a relatively high velocity and is divided into a portion which passes through pump outlet means in the form of a discharge passage 16 communicating with chamber 15 and a discharge port 17 from which this portion of fluid is discharged from the body of fluid 11 and container 10. Another portion of fluid passing through pump chamber 15 is diverted from the part discharged through the outlet and is recirculated through passages 18 and projected directly into a body of fluid 11 and toward the bottom 19 of the container for effectively stirring the body of fluid 11.

In the preferred embodiment of the invention as illustrated in the drawings, pump 12 is an immersion type centrifugal pump having a housing 25 and within an upper end of this housing is a motor (not shown) for rotatably driving an impeller shaft 26 and an associated impeller 27 received in chamber 15 and mounted in housing 25 for rotation about an axis indicated by reference numeral 28. Impeller 27 has a cylindrical body portion 30 concentric with axis 28 and including a centered depending boss 31. Suitable impeller blades 32 extend generally radially outwardly from boss 31 and depend from body 30. Impeller 27 is driven in one direction during pumping operation, and as indicated by the arrow in FIGURE 2, more particularly in a counterclockwise direction.

Passages 18 and inlet 14 are formed in an end cover 35 part or plate 35 of housing 25. Part 35 has an outer side 36 generally parallel to and spaced from the container bottom 19, with depending legs 37 facing the container bottom. An inner face 38 of part 35 is immediately adjacent and generally parallel to the series of impeller blades 32. Passages 18 define jet nozzles for projecting fluid from chamber 15 directly into the body of fluid 11 at container bottom 19. This projected fluid has a high velocity and engages the bottom and sides of the cylindrical container to move in a revolving whirl-like direction with a component of movement away from part 35 and toward bottom 19. More particularly, passages 18 are each inclined downwardly toward the outer side 36 of part 35 and container bottom 19 and in the direction of rotation of impeller 27 adjacent each passage 18 to create turbulence in the body of fluid 11, both in a horizontal direction caused by the revolving movement of jets of fluid and in a vertical direction caused by an axial component of movement of the jet toward and against container bottom 19 from which the turbulent flow of fluid is upwardly.

In order to provide even mixing of a fluid within container 11, the container bottom 19 is preferably circular with axis 28 intersecting the center of bottom 19. As illustrated in FIGURE 1, container 10 is in the form of an open topped cylindrical tank having a closure 40 which receives a flange 41 of pump housing 25 to support the pump with its lower end extending through an opening 42 in cover 40.

In operation of the fluid handling apparatus the impeller 27 is rotated by its motor for pumping part of the body of fluid 11 through inlet 14 and into pumping chamber 15, thus increasing the pressure and confining this portion of the fluid. A portion of the fluid in chamber 15 is discharged out of the body of fluid 11 and container 10 through discharge passage 16 and discharge port 17. Another portion of the fluid passing through chamber 11 is discharged through passages 18 and forms

high velocity jets moving in a path for effectively stirring the body of fluid 11, as previously described.

In addition to the turbulence imparted to the body of fluid 11 by the jets of fluid projected from passages 18, additional turbulence and stirring is provided as the fluid enters inlet port 14 in the center of cover part 35. Thus the pump inlet cooperates with jet passages 18 to provide effective stirring of the body of fluid.

The apparatus is particularly useful in forming a mixture or suspension of particles in a liquid, and by concurrent stirring and delivery of the suspension, a more nearly perfect suspension or mixture may be obtained than if each operation is carried on individually, particularly since the inlet means 14 are located at the general area of maximum stirring and intermixing of the ingredients in container 10. The illustrated embodiment of the invention has been found to mix particles and liquids about 10 to 15 times faster than available mechanical agitators.

I claim:

1. Fluid handling apparatus comprising: a container having a generally cylindrical wall for holding a fluid, said container having a generally circular bottom, an immersion type centrifugal pump having a pumping chamber and an impeller in said chamber, said impeller being mounted for rotation about an axis generally normal to the center of said bottom, and said impeller having blades extending generally radially about said axis, said pump having inlet means at the bottom of said chamber communicating with said chamber for the passage of said fluid from said container into said chamber 30 and outlet means communicating with said chamber for discharging a portion of said fluid from said container, means for rotating said impeller in one direction about said axis to pump said fluid through said chamber; a cover plate having a side facing said bottom and an opposite side defining a wall of said chamber generally parallel to and facing said blades, said plate having a series of passages, said series being generally concentric about said axis and opening through said plate, said passages being similarly inclined generally in the direction of rotation of the impeller adjacent the respective passage and toward said container bottom for directing high velocity jets of fluid from said chamber in a direction angling

toward said bottom and container wall for producing rotary turbulence and effective stirring of the body of fluid.

2. Fluid handling apparatus comprising: a container for holding a fluid and having a bottom, an immersion type centrifugal pump having a pumping chamber and an impeller in said chamber, said impeller being mounted for rotation about an axis generally normal to said bottom, and said impeller having blades extending generally radially about said axis, said pump having inlet means at the bottom of said chamber communicating with said chamber for the passage of said fluid from said container into said chamber and outlet means communicating with said chamber for discharging a portion of said fluid from said container, means for rotating said impeller in one direction about said axis to pump said fluid through said chamber; a cover plate having a side facing said bottom and an opposite side defining a wall of said chamber generally parallel to and facing said blades, said plate having a series of passages, said series being generally concentric about said axis and opening through said plate, said passages being similarly inclined generally in the direction of rotation of the impeller adjacent the respective passage and toward said container bottom for directing high velocity jets of fluid from said chamber in a direction angling downwardly but away from said bottom for producing revolving movement of the body of fluid, and said plate having a central opening defining said inlet means.
